JOHN E. DOBSON, OF CLEVELAND, OHIO, ASSIGNOR TO THE CLEVELAND PUNCH & SHEAR WORKS COMPANY, OF CLEVELAND, OHIO, A CORPORATION OF OHIO

PRESS FOR FORGING OR SHAPING METAL

Application filed December 27, 1926. Serial No. 157,107.

This invention relates to presses for forging or shaping metal, and more particularly to presses of the type wherein the metal to be forged or shaped is held between clamping dies or members while subjected to the action of a forging or shaping die. While the invention shown and described herein is particularly applicable to presses for forging metal, it will be evident that it is capable of use in connection with other types of presses and machines.

It is the general purpose and object of the invention to provide a press of this character with means whereby the metal to be forged or shaped is held firmly clamped prior to the actual engagement of the forging or shaping die therewith and is retained in such clamped position until after the said die shall have completed its forging or shaping operation.

20 A further object of the invention is to secure a sufficient dwell of the work-clamping member against the work to clamp the latter during the entire period that the forging or shaping die is in engagement therewith and 25 without recourse to cams or cam shafts which have proven unsatisfactory for this purpose, especially in heavy forge-press operations.

A still further object of the invention is to enable the shaft by which the forging or 30 shaping die is reciprocated to operate a work-clamping member in such manner as to produce a dwell in such member while in work-engaging position meanwhile operating such member by means of a connection 35 which moves continuously with the shaft.

I accomplish the foregoing object and other and more limited objects which will be set forth hereinafter, in and through the construction and arrangement of parts shown in 40 the drawings hereof, wherein Fig. 1 represents a front elevation of a press embodying my invention and showing the parts in the positions which they occupy when the forging or shaping die is at the bottom of its stroke; Fig. 2 is a view, similar to Fig. 1, showing the positions of the parts when the forging or shaping die is at or near the top of its stroke; Fig. 3 is a side elevation of the said machine, with the parts as shown in 45 Fig. 1; Figs. 4, 5 and 6 are diagrammatic

views showing the relative positions of the parts for operating the movable clamping die from the drive shaft, in different angular positions of said shaft; and Fig. 7 is a diagram illustrating the relative movements 55 of the forging or shaping die and of the movable clamping die during a revolution of the driving shaft.

Describing the various parts by reference characters, 1 represents the bed of a press 60 of the forging or punching type, and 2 the supporting base for said bed. From one side of the base there projects a shelf 3, said shelf being provided with a guide channel 4 in the upper surface thereof for the reception of 65 toggle links, to be described hereinafter.

Supported by the base 2 are uprights 5. 6 Denotes a shaft which is mounted in journals provided in the tops of the uprights 5 and in the bottom of a cap 7 secured to said 70 uprights by bolts 8. The shaft projects beyond the uprights and has one of its ends supported in a bracket 9 extending outwardly and upwardly from one of said uprights. Driving means, as a pulley 10, is applied to 75 the shaft between the bracket 9 and the adjacent upright 5.

About midway between the uprights 5, the shaft is provided with an eccentric 11 on which is mounted the collar 12, said collar 80 having a rod 12^a extending downwardly therefrom and carrying at its lower end a cross head 13 to the bottom of which the forging die 14 is secured. The cross head 13 travels between guides 15 on the uprights 5. 85 The end of the shaft 6 which is opposite the bracket 9 extends beyond the upright at such side of the press and is provided with a crank 16, the pin 16^a whereof has a block 17 journaled thereon, the said block being provided with trunnion pins 18 to which the upper end of a link 19 is journaled by means of forks 19^a. The bottom of the link 19 is forked, as shown at 19^b, and these forks are connected by trunnion pins 20^a with a block 20, the said block having trunnion pins 20^b extending at right angles to the pins 20^a to which one arm 21 of a bell-crank lever is connected by means of forks 21^a. 90 95

The bell-crank lever is pivoted at the angle 100

between its arms 21 and 22 to a lug 23 on the adjacent upright 5 by means of a stud 24 extending through the said lug and through a hub 25 on said lever. The lower end of the lever arm 22 is forked, as shown at 22^a, and is connected by a pin 26 with the upper end of a link 27, the lower end whereof is connected to the joint 28 between a pair of toggle links 29 and 30. The link 29 is hinged at 31 to a block 32 anchored within the channel 4 by a flange 32^a overhanging the shelf and secured thereto by a screw bolt 32^b. The end of the link 30 which is opposite the pivot 28 is hinged at 33 to a die carrier 34 to which the movable clamping die 35 is secured, the said die carrier and die being movable along the top of the bed 1, the channel 4 constituting a continuation of such bed top. Opposed to the movable die carrier 34 and die 35 are the die carrier 36 and the fixed die 37.

As will appear from the first three figures of the drawings, when the forging die 14 is in its lowermost position (as shown in Fig. 1) the links 29 and 30 will be straight, with the die 35 in its innermost position—where it is in closest proximity to the fixed die 37. When the die 14 is in its uppermost position (as shown in Fig. 2), the parts 19, 21, 22 and 27 will have been moved upwardly by the shaft 6 so that the joint 28 will have been elevated, withdrawing the movable die 35 from its clamping relation with respect to the fixed die 37. In order, however, to obtain a sufficient dwell in the clamping position of the die 35 to enable the work or object subjected to the foregoing operation to be held firmly, not only at the time of impact of the die 14 against such work or material, but prior thereto and until said die shall have completed its forging or shaping stroke, special connections between the shaft 6 and the die 35 are necessary; also a special relation must exist between the positions of the eccentric 11 and the crank 16 with relation to the shaft 6. The special connections are those afforded by the parts 19, 21, 22 and 27, and the toggle links 29 and 30, and the manner in which these connections operate to secure the foregoing result will be explained in connection with the diagrammatic views in Figs. 4-7, inclusive. It should be noted that the parts 16, 19, 22, 27, 29 and 30 are so constructed as to constitute three pairs of toggles, parts 16 and 19 forming the first pair, parts 22 and 27 the second pair, and parts 29 and 30 the third pair, and that these toggles are so arranged that the first toggle 16-19 is connected to the shaft 6, the third toggle 29-30 is connected to the clamping die 35 and the second toggle 22-27 connects the first and third toggles. This arrangement of the three pairs of toggles, and the setting or timing of the crank 16 and the links forming the toggles is such as to produce a prolonged dwell of the clamp-

ing die 35 in clamped position and in timed relation to the forging die 14.

Referring first to Figs. 4, 5 and 6, the circle C represents the path of the crank pin 16^a and of the extreme projection or high spot of the eccentric 11 during one revolution of the shaft 6, it being assumed, for convenience of illustration, that the said crank pin and such projection of the eccentric are equidistant from the center of rotation of the shaft 6. In Fig. 4, the parts are shown in full lines in the positions which they occupy in Fig. 2, and the direction of rotation of the shaft 6 is that indicated by the arrow. As will appear from this view and the two succeeding views, the crank pin 16^a is about 45° in advance of the high spot or extreme projection of the eccentric 11. In this view, it will be observed that, while the crank pin 16^a is on its upper center, the link 19 is "off center"; that is to say, it extends at an angle with respect to a line D connecting the center of the shaft 6 and the joint 28 between the toggle links 29 and 30; also, the link 27, which is connected with the lower arm 22 of the bell-crank lever, extends at an angle from the toggle joint 28 and in the general direction of the link 30.

In Fig. 5, the parts are shown in the positions which they will occupy when shaft 6 shall have turned about 135° from the position shown in Fig. 4, which will have resulted in pushing downwardly upon the link 19 and in rocking inwardly the lever arm 22 so that said arm and the link 27 are nearly in a straight line coinciding with part of the line D. In this position, it will be seen that the toggle links 29 and 30 are almost straight; and, as will appear by reference to the positions of the parts marked 11 and 16^a, the die 14 will have completed only about one-half of its downward stroke.

In Fig. 6, the parts are indicated in the positions which they will occupy when the crank pin shall have reached its lower center with the die 14 approaching its bottom center. At this time, the link 19 will have been moved downwardly from the position shown in Fig. 5, throwing the lever arm 22 to the right of the line D; but the links 29 and 30 will be in substantially the same position as shown in Fig. 5; that is to say, they will be substantially straight and will obviously be holding the movable die 35 in substantially its innermost position, so that the object or material clamped between it and the fixed die will be held firmly.

In Fig. 4 there are shown in dotted lines the positions which the parts occupy when the die 14 is at the bottom of its stroke. In this position the "high spot" or extreme projection of the eccentric is on the bottom center and in a line extending downwardly from the center of the shaft 6. The crank pin 16^a is approximately 225° from its original posi-

tion, and the connections between the crank pin and the toggle links 29 and 30 have resulted in bringing the lever arm 22 and the link 27 in a straight line, with the result that the toggle links 29 and 30 are also in a straight line, so that the work or material between the dies 35 and 37 is subjected to the maximum possible clamping action at the time when the forging die 14 is at the bottom of its stroke and exercising its final forging or shaping action upon the material or work.

It will be seen, from the diagrammatic views in Figs. 4-6 inclusive, that the links 29 and 30 are held in substantially straightened position, not only during 90° of the revolution of the shaft 6, but for a considerable period thereafter, as the said links are actually straight at the end of the 90° -period shown in said views. As a matter of fact, the links 20 are held in such substantially straightened position during about 120° of the rotation of the shaft 6.

In Fig. 7 I have shown, by the upper curved line F—D and the lower curved line C—D, the relative positions of the forging die and of the movable clamping die, respectively, throughout a complete revolution of the shaft 6. In this view, the degrees through which the shaft 6 rotates while making a complete revolution are indicated by horizontal spaces of 10° each. The extent of the vertical movements of the forging die during such revolution is indicated by the vertical lines extending upwardly from the line F—D. The positions of the movable die meanwhile are indicated by the lower line C—D, and the extent of its movements toward and away from the fixed die by the vertical lines extending downwardly from the line C—D. In practice, the crank pin 16^a is 45° in advance of the high spot of the eccentric 11. This brings the highest point of the line C—D 45° in advance of the highest point on the line F—D, as shown at the right of Fig. 7. By comparison of the lines F—D and C—D with each other, it will be seen that the die 35 is moved to approximately its innermost clamping position when the "high spot" of the eccentric shall have been moved approximately 90° downwardly and at the time when the crank pin 16^a shall have moved approximately 135° downwardly, and that the die is held in such position until after the high point of the eccentric shall have passed its lower center (180°).

By arranging the link 19 at an angle to the line D, as shown, and by employing in effect two toggle connections between the lever arm 21 and the movable die (one at 22, 27 and the other at 29, 30) operating at right angles to each other, the calculated movement of the die 35 during approximately 120° of the revolution of the shaft 6 amounts to only about $15/10,000$ inch; and, in practice, this movement is negligible as affecting detrimentally

the clamping of the work or metal which is operated upon by the die 14. This arrangement also enables the dies 35 and 37 to exercise a powerful gripping action upon the work throughout the entire period of the dwell of the die 35.

By virtue of the construction and arrangement of the parts shown herein, it is possible to operate the forging die and the movable clamping die from a common shaft and to perform heavy forging operations throughout a long period of time without injury to the mechanism. Furthermore, it is possible to secure these results by means of an attachment to an existing type of press and without the employment of cams, which have proven unsatisfactory when used to perform work of this character; and the cost of such equipment and installation is relatively inexpensive.

For convenience of description, the forging die is assumed as being movable downwardly toward the clamping dies 35 and 37 so that it will have reached the bottom of its stroke when it is nearest said clamping dies, and corresponding descriptive terms are employed herein. However, it is not intended, by this language, to limit my invention to use in connection with only a vertically movable cross head and forging die and a horizontally movable clamping die, as it will be evident that, so far as the movement of the dies and the mode of accomplishing the same is concerned, the same result could be accomplished with the forging die movable in other than a vertical direction and with the movable clamping die movable in other than a horizontal direction.

Having thus described my invention, what I claim is:

1. In a machine of the type described, the combination of a shaft, a forging or shaping die, connections between said shaft and said die for reciprocating the latter by the rotation of the said shaft, a movable clamping member, and connections between the said shaft and the said member for moving the latter into engagement with the work, the said connections comprising a toggle one of the links of which is connected to the movable member, a toggle operating at substantially right angles to the first-mentioned toggle and comprising a link connected to the joint of said first toggle, and connections between the last-mentioned link and said shaft, including a crank arm carried by the shaft, and a bell crank lever between said crank arm and toggle, the said second toggle prolonging the dwell produced by said first toggle.

2. In a machine of the type described, the combination of a shaft, a forging or shaping die, connections between said shaft and said forging or shaping die for reciprocating said die by the rotation of said shaft, a movable clamping member, and connections between

- the said shaft and the said member for moving the latter toward and from the work, the said connections comprising a pair of toggle links, one of which is connected to the said member, a crank carried by said shaft, the said crank having a crank pin, a block journaled on said crank pin, a link having a swiveled connection with said block, a bell-crank lever, a universal connection between one of the arms of said lever and the opposite end of said link, a link connected at one end with the joint of said toggle, and a pivotal connection between the opposite end of said link and the other arm of said lever.
3. In a machine of the type described, the combination of a shaft, a forging or shaping die, connections between said shaft and said die for reciprocating the latter by the rotation of said shaft, a movable clamping member and connections between the said shaft and the said member for moving the latter into engagement with the work, the said connections comprising a toggle, one of the links of which is connected to the movable member, a second toggle comprising a link connected to the joint of the first mentioned toggle, and means operated by the rotation of said shaft for operating said link, said second toggle prolonging the dwell produced by said first mentioned toggle.
4. In a machine of the type described, the combination of a shaft, a forging or shaping die, connections between the said shaft and said die for reciprocating the latter by the rotation of the said shaft, a movable clamping member, and connections between the said shaft and the said member for moving the latter into engagement with the work, the said connections comprising a toggle, one of the links of which is connected to the movable member, a second toggle operating at substantially right angles to the first mentioned toggle and comprising a link connected to the joint of said first toggle and connected between the last mentioned link and said shaft, the said second toggle prolonging the dwell produced by the said first toggle.
5. In a machine of the type described, the combination of a shaft, a forging or shaping die, connections between said shaft and said die for reciprocating the latter by the rotation of the said shaft, a movable clamping member and connections between the said shaft and the said member for moving the latter into engagement with the work, the said connections comprising a toggle, one of the links of which is connected to the movable member, a second toggle comprising a link connected to the joint of the first mentioned toggle and means connecting the said second toggle with the shaft whereby the toggle links of the two toggles will be substantially straightened and the movable member held in clamping relation with respect to the work before the said die shall have

reached the end of its forging or shaping stroke and will be held in such substantially straightened position until after the said die shall have completed such stroke, the said second toggle prolonging the dwell produced by the said first toggle.

6. In means for operating the heading and die clamping dies of a forging machine, a heading die, a clamping die, a crank shaft having a main crank and an auxiliary crank set at an angle of at least 45° ahead of the main crank, the said main crank being coupled to the heading die for operating the same, and a three-fold toggle lever mechanism connecting the auxiliary crank and the clamping die and coacting with said auxiliary crank on each cycle of action of the machine to start the closing of the clamping die before the heading die has started its heading stroke, the three-fold toggle lever mechanism giving a prolonged dwell to the clamping die.

In testimony whereof, I hereunto affix my signature.

JOHN E. DOBSON.
